(57) **CLAIM**

I claim the ornamental design for a water filter air lock clip, as shown and described.

DESCRIPTION

FIG. 1 is a right-front perspective view of a water filter airlock clip showing the design thereof.

FIG. 2 is a left-rear perspective view of the water filter airlock clip.

FIG. 3 is a front perspective view of the water filter airlock clip.

FIG. 4 is a rear perspective view of the water filter airlock clip.

FIG. 5 is a left perspective view of the water filter airlock clip.

FIG. 6 is a top perspective view of the water filter airlock clip; and,

FIG. 7 is a bottom perspective view of the water filter airlock clip.
